US0D1046817S

(12) **United States Design Patent** (10) **Patent No.:** **US D1,046,817 S**
(45) **Date of Patent:** **** Oct. 15, 2024**

(54) **AUDIO SPEAKER**

(71) Applicant: **Xuefeng Xia**, Xuancheng (CN)

(72) Inventor: **Xuefeng Xia**, Xuancheng (CN)

(**) Term: **15 Years**

(21) Appl. No.: **29/878,592**

(22) Filed: **Jun. 25, 2023**

(30) **Foreign Application Priority Data**

Apr. 13, 2023 (CN) 202330199102.0

(51) **LOC (14) Cl.** **14-01**

(52) **U.S. Cl.**

USPC **D14/215**; D14/216

(58) **Field of Classification Search**

USPC D14/215, 216, 204, 209.1, 212, 496,

D14/203.1, 203.3, 203.6; 381/334

CPC H04R 25/00; H04R 25/02; H04R 1/02;

H05K 5/00; G09G 5/00

(57) **CLAIM**

The ornamental design for an audio speaker, as shown and described.

DESCRIPTION

FIG. 1 is a front, left and top perspective view of an audio speaker, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the audio speaker that form no part of the claimed design.

1 Claim, 8 Drawing Sheets
